UNITED STATES PATENT OFFICE.

WALTER A. NIVLING, OF BOSTON, MASSACHUSETTS.

COATING APPARATUS.

1,236,002.

Specification of Letters Patent.

Patented Aug. 7, 1917.

Application filed April 15, 1916. Serial No. 91,300.

To all whom it may concern:

Be it known that I, WALTER A. NIVLING, a citizen of the United States, and residing at Boston, in the county of Suffolk and State of Massachusetts, have invented a new and Improved Coating Apparatus, of which the following is a specification.

This application is a continuation in part of my application Serial Number 864,402, filed October 1st, 1914.

This invention relates to means for and a process of maintaining the supply of liquid, such as starch sizing, in receptacles wherein yarn, webs, fiber or other material 15 is to be immersed and coated or impregnated.

The strength or sizing value of starch sizing is dependent upon preserving the liquid in the same condition as when freshly made. 20 The starch-solution is not a true solution but rather a crude or colloidal solution carrying in suspension undissolved skeletal forms of starch granules, and whenever these skeletal forms are removed, or broken 25 down by agitation, or if the solution is allowed to cool and then re-heated, the service is greatly impaired. The condition is more clearly understood after microscopic tests 30 of two solutions of the same percentage strength—one fresh and the other having been subjected to long boiling, to cooling and re-heating, or to excessive agitation. In the first case the skeletal forms are seen to crowd one another and to influence the rate 35 of flow or viscosity; in the latter, the viscosity has been largely reduced by a breaking down of the skeletal forms. The deterioration to a point wholly unfitting it for sizing work can, in extreme cases, be 40 brought about in as short a time as thirty minutes.

The effect of lessening the body or viscosity by destroying these skeletal forms is that less size is taken up by the yarn or 45 by the web of the cloth and less retained after the yarn or cloth passes the squeeze rollers. Every slasher attendant or cloth finisher recognizes the effect of "running down" of his size. At frequent intervals he 50 passes his fingers between the opening threads at the lease rods. The difference in the adhesive bond between adjoining threads is immediately apparent. When there is an evidence of insufficient size on the yarn or

cloth, he tries to restore the desired condition 55 by adding a fresh lot of size which has not become vitiated or run down. It is evident therefore that conditions are constantly changing and at no two times is the size exactly the same. A greater or less amount is 60 obviously on different parts of the warp, due in part to there being strong size in the size box at some times and weak size at others, due also to the variations in the amount (volume) of size in the size box. 65

It will be seen from the foregoing that an ideal condition would be constant level (volume) of size in the size box and a continuous renewal with strong size that would keep a uniform consistency every hour of 70 the day.

This requires a continuous addition of prime size equal to or preferably in excess of the requirements of the yarn or cloth passing through the size box or mangle. 75 Inasmuch as the rate of travel is subject to many variations due to stopping to change beams, slowing down or speeding up after breakout or laying in a set, etc., it is impossible to so regulate a stream of size as to 80 meet these variations.

From what has been previously pointed out relative to causes of deterioration of starch size solutions, measures for securing full service from starch in sizing must also 85 go back of the size box or mangle and include the proper preparation and handling of size. In many starches not well made or purified there will be found agglomeration of starch grains, held together by impurities, gluten, or cellular tissue. Unless every granule of starch is separated from its neighbor a uniform solution free from lumps cannot be secured. It is therefore advisable to agitate the starch very thoroughly, 90 violently in fact, while slowly heating to boiling and then continuing the boiling until the whole mass has come to solution. Having brought the solution to a thorough boil, it should be sent through a strainer to 100 a storage kettle, from which the several slashers or mangles are supplied. In this kettle the agitation should be reduced to just enough to maintain a uniform temperature and suspension, as unnecessary agitation is injurious. This kettle should preferably be steam-jacketed or insulated. 105

All starch solutions undergo change on

standing, which lessens their sizing value. It is therefore advantageous to supply several slashers from one kettle, as by so doing the size is used up while in prime condition. In the customary arrangement, size suffers great impairment of quality from too much agitation, from too long a time elapsing from the time of preparation to the time of use, and to deterioration and 10 damage from lumps and skins formed by changes in temperature.

Heretofore in sizing yarns for weaving, the sizing liquid or "size" has been drawn into the size boxes intermittently, usually 15 through pipes of from one and one-half to two and one-half inches in diameter so as to fill the boxes quickly. The valves were then closed, which allowed the size remaining in the pipes to cool and congeal; or, in 20 those cases in which efforts were made to maintain a circulation, the path of the liquid was a circuit from the supply kettle through a pump and pipe line back to the kettle. This gave rise to "dead ends" adjacent the 25 slashers or elsewhere; in other words, did not include the whole size supply lines, which merely localized the trouble. Also, on account of the continuous and rapid pumping of the major portion of the whole 30 mass in previous systems, the circulation referred to is rapid—a kettle of size being ordinarily handled by the pumps in from three to five minutes, the size therefore being subject to violent agitation, 35 which takes away from its body. One often hears the expression "the life has all been pumped out of the size." This is actually the case—the size has been deteriorated; it not only lacks its original value but the last 40 of the kettle is very much inferior to the first portion from this cause alone.

It was impossible to reduce the supply through these pipes of relatively large diameter so as to get a stream approximately equal to the rate of consumption of size by the yarn traveling through the size box, owing to the elliptical opening formed when throttling down a valve of large diameter. The valve and valve walls were 45 in such close proximity, when the opening was reduced to correspond to or slightly exceed the rate of consumption of size, that they would not permit a continuous flow. Very small particles of foreign matter or 50 congealed size, carried in the size, would obstruct the opening so that no continuous supply could be maintained except by a large opening and large volume of size, which is objectionable for reasons already 55 pointed out.

I have found that a specially constructed feed device giving a circular opening of, say, one-half to one-fourth of an inch in diameter, according to the thickness of size, 60 amount and character of yarn being sized,

and the head under which the opening is placed, and optionally a larger opening for quickly starting up the machine, will not become clogged and will supply a substantially uniform quantity of sizing liquid 70 sufficient to equal or slightly exceed that consumed in the sizing box. The slight excess which, for example, may be ten to twenty per cent. of that brought to the machine can be returned to the source and re-used, thus preventing the impairment of the remaining eighty or ninety per cent.

With the foregoing in mind, the nature of the present invention will be more readily understood. It consists in means for and a 80 process of preparing, distributing and applying the size whereby the deterioration caused by cooling and re-heating, by an excess or by an insufficient quantity in the size machine, by agitation and by time is 85 much reduced, and whereby the size in a particular slasher or size box may be renewed and sizing quality maintained, approximately in accordance with the demands of the material being treated therein; 90 also in means whereby the strength of the size in the size box may be continuously and accurately controlled and whereby a constant volume may be maintained; in means whereby an active size of a desired strength 95 may be supplied to a given slasher by blending sizes of different strengths contained in separate storage receptacles; in means whereby active sizes of different strengths may be supplied to different size boxes by 100 separately blending in different proportions sizes of different strengths derived from a plurality of storage receptacles; in means for rapidly mixing a batch of size by violently agitating the ingredients thereof when 105 first preparing, and thereafter delivering the batch to a storage receptacle that includes means for agitating the batch less violently; in means for delivering the batch from the mixer to either one or a plurality of storage 110 receptacles; in means for circulating the size through a path that includes the size box and the storage receptacle, thus avoiding "dead ends"; in means for applying steam to the pipes for the purpose of heating or cleaning; in sight devices so located 115 as to allow ready observation of the flow of size from the several sources together with the action of the steam; means whereby the level of the sizing liquid in the receptacles 120 may be controlled and whereby the receptacles may be readily drained; and in the use of valves having small and large circular passageways, as above suggested.

The invention also consists in the details 125 of construction shown, described and claimed.

In the accompanying drawings, Figure 1 is a diagrammatic perspective of one embodiment of my invention. Fig. 2 is a lon- 130

itudinal section through a three-way valve shown in Fig. 1. Fig. 3 is a section on the line 3-3 of Fig. 2. Fig. 4 is a vertical section through one of the tanks. Fig. 5 is a fragmentary elevation showing a modification in the piping. Fig. 6 is a similar view illustrating another modification. Fig. 7 is a longitudinal section through the fluid level controlling device. Fig. 8 is a section 10 on the line 8-8 of Fig. 7 with one of the gates lowered. Fig. 9 is a plan view corresponding to Fig. 7. Fig. 10 is a perspective view of the gate shown in Figs. 7, 8 and 9. Fig. 11 is a vertical section through a sight 15 device whereby the flow of sizing liquid may be observed. Fig. 12 is a section on the line 12-12 of Fig. 11.

Similar reference characters refer to like parts throughout the several views.

20 In the embodiment of the invention shown, the sizing is mixed in the make-up kettle or tank 100 (which is provided with an agitator of any approved character, such, for example, as the agitator 101 driven by gearing 102, shaft 103 and pulley 104, illustrated in Fig. 4), and is pumped therefrom through the pipes 105, 106, 107 and 108 and valves 109 by a pump 110 and delivered through screen boxes 111 of suitable form into storage receptacles 1 and 2 in batches of different strengths. The storage kettles 1 and 2, for convenience, are made of greater capacity than the kettle 100. The make-up tank and the storage tanks, particularly the latter, 35 are each preferably jacketed to receive steam from a main 39 through the pipes 112 and valves 113, and each of the tanks is provided in its top with a door 114 which may be latched in closed position by any desired 40 means (not shown). Each of the storage receptacles is also equipped with an agitator which may be the same as or different from that heretofore described. In use, however, the agitator in the mixing tank is run 45 at high speed to cause a rapid mixing of the ingredients, whereas the agitators in the storage receptacles run but slowly, thus avoiding the deterioration due to excessive agitation.

50 The sizing liquid is supplied from the storage tanks 1 and 2 by piping hereinafter described, to the sizing boxes or slashers 3 in which yarn, web or other material to be coated may be subjected to the sizing liquid 55 by the action of the rolls 6, 7, 8 and 9, or in any other desired manner. The level of the liquid in the sizing receptacles may be controlled and the excess liquid may be returned to the storage tanks by instrumentalities, the details of which will be pointed out later.

Leading from the storage tanks 1 and 2 through the valves 11 and 12 are the supply pipes 13 and 14 that connect, respectively, to 65 the line pipes 15 and 16. Each of the latter

is provided with a T 17 from which a short pipe 18 leads to a three-way valve 19, best shown in Figs. 2 and 3. The valves 19 are preferably provided with a longitudinal circular passage 20, and the transverse relatively smaller circular passage 21 across which extends the rotatable valve member 22, that may be tapered, and is held in place by the usual stem 23, nut 24 and washer 25, the end opposite the nut being provided with means, such as the rectangular portion 26, to which force may be applied in an obvious manner. The rotatable member is preferably provided with the circular opening 27 of substantially the same size as the passage 20, from which leads the circular lateral opening 28 of substantially the same diameter as the passage 21. The valve may obviously be turned to afford an unobstructed flow of liquid through the passage 20 and opening 27, or to afford a restricted flow through the opening 28, the opening 27 and the passage 21 (Fig. 3); it may be turned so as to entirely prevent the flow, or it may be turned to connect the passage 21 with the lower end of the passage 20.

The said lower ends of the passages 20 communicate with the Y 31 through the nipples 32, fittings 33 and pipes 34; and from the lower end of the Y the pipe 35 leads downwardly into the sizing receptacle. The passages 21 may lead laterally through the pipes 36 to a sight device 37 that may be connected, by means of the pipe 38, to a main steam pipe 39 supplied with T's 40, 100 the valves 41 being inserted to control the admission of steam; and extending downwardly from the sight device to the sizing receptacle is the pipe 42 having the valve 43. See modified construction in Fig. 6. 105

It will therefore be seen that either of the three-way valves may be turned to fill the sizing receptacle quickly through the pipe 35, after which it may be positioned to afford a smaller flow through the pipes 36-42, 110 steam being admitted at the same time through the pipe 38, if desired, to heat the liquid or to dilute it and render it less viscous. Should the pipe 18 become clogged, the valve 43 may be closed and the valve 41 115 opened, whereupon steam will flow through the pipe 36, passage 21 and openings 27-28 up into the pipe 18; and should the pipes below the valves 19 become clogged, the valve plugs can be so turned that the openings 28 face downwardly, whereupon the steam will pass down into the pipes 34-35. Usually, however, the smaller pipes only are liable to clog, and these pipes can be easily cleared by the jets of steam. 120 125

Duplicate installations are indicated by dotted lines in Fig. 1, but it is apparent that these may be omitted. The primary purpose of the provision of two tanks 1 and 2 is to allow the use of sizing liquids of different 130

strengths. It is clear that, by properly manipulating the valves, the weak liquid, say, may be brought to the receptacle 3 from the tank 1, or the strong liquid may be 5 brought from the tank 2, or liquid may be brought to the receptacle 3 in definite proportions from both of the tanks and simultaneously mixed to the proper consistency. It is also clear that liquid of a given strength 10 may be supplied to one of the receptacles 3, and that liquid of another strength may at the same time be supplied to each of the others.

The sight device 37 (Figs. 11 and 12) 15 comprises a tubular body 50 having the threaded ends 51 on which are received the threaded glass retaining rings 52 having the inwardly extending flanges 53 whereby the sight glasses 54 are secured in place, packing rings 55 and 56 being interposed between the glass and the adjacent surfaces. The inner surface of the body merges at both top and bottom into the flaring deflectors 57 and 58 that, as shown, are of 20 frusto-conical form and surround, respectively, the extended lower end 59 of the pipe 38 (that may enter the body through a bushing 60 whereby pipes of different sizes may be accommodated by a single opening in the 25 body), and the upper end of the pipe 42 (which may likewise be received in a bushing 61). The pipes 36 enter the body from the side and extend out over the upper end of the deflector 58 so as to discharge their 30 contents well within the latter. The flow of liquid and steam is thus rendered visible and contact of the liquid with the glasses 54 is prevented.

The supply of liquid to the tank 3 in excess of that required is conducted through 40 the short pipe 63 to the level-controlling device 64, from which a pipe 65 leads through the valve 66 to the sewer 67. Also leading from the level-controlling device is a second 45 pipe 68 that may be brought, by means of the three-way valve 69 and pipes 70, into communication with either of the pipes 71 or 72 from which the liquid may be returned to the tanks 1 and 2 through the 50 screen boxes 111 by means of the pipes 120, pumps 121 and pipes 122. Sight devices 73, similar to that already described, may be inserted in the pipes 65 and 70, in which case the openings corresponding to the pipes 36 55 should be closed by plugs 74.

The level-controlling device (Figs. 7, 8, 9 and 10) comprises the tank having the bottom 76 and the preferably curved ends 77. The pipes 63 and 65 enter the tank near 60 one end, and the pipe 68 is threaded into the bottom of the tank near the opposite end. At a point between the pipe 68 and the pipes 63-65 the side walls of the tank are joined by a partition 78, the lower end of which 65 is cut away to form the passage 79 and the

upper end of which is cut away to form the opening 80. Adjacent the edges of the passage 79, the partition is provided with the short opposed dove-tailed guides 81, between which a gate 82 having the handle 83 is 70 adapted to slide. Upon the opposite side, the partition has formed thereon the dove-tailed guides 84, between which the gate 85 may be guided. This gate preferably includes a threaded lug 86 through which 75 passes the adjusting screw 87, the lower end of which contacts with the bottom of the tank and the upper end 88 of which may be squared or otherwise adapted to receive an application of force whereby it may be 80 turned about its axis.

The gate 82 may be positioned to close the passage 79 and the gate 85 raised until its upper edge is at the level at which the liquid is to be maintained in the sizing receptacle. The excess sizing liquid then merely runs over the top of the gate and passes off through the pipe 68. Since the 85 adjusting screw 87 is not connected to the body of the box in any way, it is obvious that it, as well as the gate 85, may be lifted bodily out of the guides, which is convenient when it becomes necessary to clean the various parts. The same is true of the gate 82.

As indicated in Fig. 6, the pipe 42 may 90 be connected to the pipe 35; and, as shown in Fig. 5, each one of the pipes 15-16 may be connected to the slashers through the nipples 125, pipes 126-127, sight device 73 and three-way valve 19 for filling the size boxes 100 rapidly, or through the three-way valve, small pipes 128, T 129 and sight device 73 for continually renewing the supply. Steam may be admitted to the sight device 105 through the pipe 130 and valve 131; and a pipe 132 (equipped with a valve 133 in case steam is to be used) affords venting means whereby a better circulation is insured.

Review of operation.

Batches of size of different strengths are 110 rapidly mixed in the mixer 100 by running the agitator at a high speed, and are then pumped, respectively, into the tanks 1 and 2, in which, as before stated, the agitators 115 run slowly to avoid deterioration. The liquid from the tanks passes to the mains 15-16 from which the size boxes may be rapidly filled through the passages of larger cross-section. The valves are then turned to 120 direct the flow through the smaller pipes which may be cleaned or heated as heretofore described. The level-controlling device 64 insured immersion of the fiber at a constant depth, which, however, may be varied at will, and excess size is returned to either one or both of the storage tanks by the pumps 121. (A single pump and proper piping may, of course, be substituted for the 125 duplicate installation shown). It will be 130

observed that this circulation includes the storage receptacles and the slasher and avoids the usual dead ends. The quantity of liquid flowing being small, it follows that

5 deterioration due to circulation is practically avoided. Whenever it is desired to empty a size box, the corresponding valve 66 is opened, thus preventing the formation of skins and the like.

10 The use of a plurality of slashers supplied from the sources of different strengths proportionately reduces the time in which the size is subjected to cooling, and allows the simultaneous treatment of the material pass-

15 ing through the different slashers by active sizes of strengths which may differ from each other and from either of the sources.

While I have shown and prefer to use branch conduits comprising three-way

20 valves for conducting the sizing fluid, it is obvious that, in some cases, the three-way valves may be dispensed with and other conduits and gate valves, with passages corresponding to those in the three-way valves,

25 used in lieu thereof. It is also clear that many other changes may be made in the details of construction without departing from the spirit of my invention; and that, while the present embodiment is intended for use

30 in sizing yarn and the like, the apparatus is also applicable to coating operations generally. It will be understood that by the word "fabric" employed in some of the claims, it is meant to include either the 35 woven fabric or the yarns from which it is made. I do not, therefore, wish to be limited otherwise than as indicated by the subjoined claims.

I claim:—

40 1. A coating apparatus comprising a source of supply of coating liquid, a conduit leading therefrom, a three-way valve connected to the conduit, discharge pipes of larger and smaller diameters connected to 45 said valve, a steam pipe connected to said smaller discharge pipe, and a receptacle in which the coating liquid is used.

2. A coating apparatus comprising a source of supply of coating liquid, a receptacle in which the coating liquid is used, conduits having passageways of different cross-sectional area leading to the receptacle and through which liquid from the source may pass, and means for conducting steam 55 to the interior of one of the conduits whereby the conduit may be cleaned or the liquid may be heated.

3. A coating apparatus comprising a source of supply of coating liquid, a receptacle in which the coating liquid is used, conduits having passageways of larger and smaller cross-sectional area leading to the receptacle and through which liquid from the source may pass, and means for conducting 65 heating fluid to the interior of the pas-

sageway of smaller cross-section whereby the liquid passing therethrough may be heated.

4. A coating apparatus comprising a source of supply of coating liquid, a receptacle in which the coating liquid is used, conduits having passageways of larger and smaller cross-sectional area leading to the receptacle, and through which liquid from the source may pass, and means for conducting steam to the interior of the passageway of smaller cross-section whereby the liquid passing therethrough may be heated or the passageway may be cleaned.

5. A coating apparatus comprising a plurality of sources of coating liquid, the liquid in one of the sources being of a strength different from that in another, a receptacle in which the liquid is used, means for directing the flow of liquid from the sources to the receptacle and for regulating the amount of flow from one of the sources in respect to the flow from another source, and means for supplying steam to the interior of the directing means.

6. A coating apparatus comprising a plurality of sources of coating liquid, the liquid in one of the sources being of a strength different from that in another, a receptacle in which the liquid is used, means for directing the flow of liquid from the sources to the receptacle, and means for supplying steam to the interior of the directing means.

7. Coating apparatus comprising a source of coating liquid, a receptacle in which it may be used, conduits of larger and smaller cross-section through which liquid may flow on its way from the source to the receptacle, means for determining the conduit through which the liquid may flow, the arrangement being such that the receptacle may be quickly filled through the conduit of larger cross-section, and thereafter supplied with a regulated amount through the conduit of smaller cross-section.

8. Coating apparatus comprising a source of coating liquid, a receptacle in which it may be used, conduits of larger and smaller cross-section through which liquid may flow on its way from the source to the receptacle, means for determining the conduit through which the liquid may flow, the arrangement being such that the receptacle may be quickly filled through the conduit of larger cross-section, and thereafter supplied with a regulated amount through the conduit of smaller cross-section, and means for determining the level of the liquid in the receptacle.

9. Coating apparatus comprising a source of coating liquid, a receptacle in which it may be used, conduits of larger and smaller cross-section through which liquid may flow from the source to the receptacle, means for determining the conduit through which the

liquid may flow, the arrangement being such that the receptacle may be quickly filled through the conduit of larger cross-section, and thereafter supplied with a regulated

5 amount through the conduit of smaller cross-section, and adjustable means for determining the level of the liquid in the receptacle.

10. Coating apparatus comprising a source 10 of supply of coating liquid, a receptacle in which the coating liquid is used, a pipe leading from the source of supply, a three-way valve connected to the pipe, discharge pipes of larger and smaller cross-section connected 15 to the valve and leading to the receptacle, said valve having a passage corresponding to the pipe of larger cross-section, and also having a circular passage corresponding to the pipe of smaller cross-section, whereby 20 the receptacle may be quickly filled through the pipe of larger cross-section, and whereby coating liquid may thereafter be supplied uniformly to the receptacle to compensate for the amount used in the coating operation 25 and clogging of the passages may be largely avoided.

11. Coating apparatus comprising a source 30 of supply of coating liquid, a receptacle in which the coating liquid is used, a pipe leading from the source of supply, a three-way valve connected to the pipe, discharge pipes of larger and smaller cross-section connected to the valve and leading to the receptacle, said valve having a circular passage corresponding to the pipe of larger cross-section, and also having a circular passage corresponding to the pipe of smaller cross-section, whereby the receptacle may be quickly filled through the pipe of larger cross-section, and whereby coating liquid may thereafter be supplied uniformly to the receptacle to compensate for the amount used in the coating operation and clogging of the passages may be largely avoided.

45 12. Coating apparatus comprising a plurality of sources of liquid, a receptacle in which said liquid is used, a sight device, pipes leading from said sources of supply to said sight device, and a conduit leading 50 from said sight device to said receptacle, means for determining the flow of liquid through the first mentioned pipes, said sight device allowing the relative amounts of liquid flowing through the first mentioned 55 pipes to be observed.

13. Coating apparatus comprising a plurality of sources of liquid, a receptacle in which said liquid is used, a sight device, pipes leading from said sources of supply 60 to said sight device, means for conducting steam to the sight device at will, and a conduit leading from said sight device to said receptacle, means for determining the flow of liquid through the first mentioned pipes, 65 said sight device allowing the relative

amounts of liquid flowing through the first mentioned pipes as well as the flow of steam to be observed, whereby the conduits for the liquid may be cleaned.

14. Coating apparatus comprising a 70 source of coating liquid, a receptacle in which the coating liquid is used, a sight device, a pipe leading from said source of supply to said sight device, a second pipe leading from the sight device to the receptacle, 75 a steam pipe also leading to said sight device, said sight device comprising a body, a transparent member supported by the body, and a deflector supported by the body in position to prevent contact of the coating 80 liquid passing through the sight device with the transparent member.

15. Coating apparatus comprising a source of coating liquid, a receptacle in which the coating liquid is used, a sight device, 85 a pipe leading from said source of supply to said sight device, a second pipe leading from the sight device to the receptacle, a steam pipe also leading to said sight device, said sight device comprising a body, 90 a transparent member supported by the body, and an upwardly flaring deflector supported by the body in position to receive the discharge of coating liquid from the first mentioned pipe and prevent contact of said 95 liquid with the transparent member, and to guide the liquid to the second mentioned pipe.

16. Coating apparatus comprising a source of coating liquid, a receptacle in 100 which it may be used, conduits of larger and smaller cross-section through which liquid may flow on its way from the source to the receptacle, means for determining the conduit through which the liquid may flow, the 105 smaller conduit being circular in cross-section, the arrangement being such that the receptacle may be quickly filled through the conduit of larger cross-section, and thereafter supplied with a regulated amount 110 through the conduit of smaller cross-section.

17. Coating apparatus comprising a source of coating liquid, a receptacle in which it may be used, conduits through which the liquid may flow on its way from 115 the source to the receptacle, valve means for determining the conduit through which the liquid may flow, said valve means including a passage of larger cross-section and a passage of smaller cross-section, said last mentioned passage being circular in cross-section, the arrangement being such that the receptacle may be quickly filled through the conduit of larger cross-section, and thereafter supplied with a regulated amount 120 through the conduit of smaller cross-section.

18. Coating mechanism comprising a receptacle for coating liquid, a plurality of line pipes, a pair of three-way valves, pipes 130

connecting the same to the line pipes, main discharge pipes extending downwardly, smaller pipes extending across between the valves and joining a steam pipe and a discharge pipe, and means for controlling the flow of steam.

19. Coating apparatus comprising a receptacle for coating liquid, a source of supply and a pipe extending therefrom, a three-way valve connected to said pipe and comprising a revoluble member having passages of unequal size, discharge pipes of unequal size connecting to said valve so as to receive the liquid according to the position of the movable member, and means for conducting steam to the smaller discharge pipe.

20. Coating apparatus comprising a receptacle for coating liquid, a pair of pipes parallel to each other, a pair of three-way valves, a pair of discharge pipes connecting to said valves and then bent toward each other, means uniting said discharge pipes, a fitting between the valves, a small discharge pipe connecting each valve to said fitting, a pipe extending from said fitting to convey away the material brought to the fitting by the small discharge pipes, and a steam pipe also connecting to said fitting.

21. Coating apparatus comprising a receptacle for coating liquid, a pair of pipes parallel to each other, a pair of three-way valves, a pair of discharge pipes connecting to said valves and then bent toward each other, means uniting said discharge pipes, a fitting between the valves, a small discharge pipe connecting each valve to said fitting, a pipe extending from said fitting to convey away the material brought to the fitting by the small discharge pipes, a steam pipe also connecting to said fitting, and means mounted in the steam pipe whereby the passage of condensed steam may be observed.

22. Coating apparatus comprising a receptacle for coating liquid, a supply pipe, a three-way valve connected thereto, a large discharge pipe connected to said valve, said valve comprising a revoluble member having communicating transverse passages of unequal size, discharge pipes connecting to said valve in such a manner that either one may convey away the material passing through the valve according to the position of the revoluble member, a fitting connecting to one of the discharge pipes, a steam pipe connecting to said fitting, and means mounted in the steam pipe whereby the passage of condensed water to the liquid passing through the fitting may be observed.

23. Coating apparatus comprising a plurality of sources of coating liquid, a mixer for mixing the liquid, means for delivering the liquid from the mixer to either of the

sources at will, the liquid of one of the sources being of a different strength than that from another, a plurality of receptacles in which the liquid is used, means for directing the flow of liquid from the several sources to one only of the receptacles at a time or to a plurality of the receptacles simultaneously, and means for regulating the amount of flow from one of the sources in respect to the amount from another whereby the strengths of the liquid in the various receptacles may be accurately and continuously controlled.

24. The process of sizing which consists in mixing sizing liquid to form batches of different strengths by agitating the ingredients thereof in a mixing receptacle, delivering the size of a given strength to one storage receptacle and the size of another strength to another storage receptacle, agitating the sizes in the storage receptacles less violently than in the mixing receptacle, combining the liquids from the storage receptacles in predetermined ratio to form an active size of strength different from the strength of either of said liquids and causing the active size to circulate in a path that includes one of the storage receptacles and a slasher in which it may be used.

25. The process of sizing which consists in mixing sizing liquid to form batches of different strengths by agitating the ingredients thereof in a mixing receptacle, delivering the size of a given strength to one storage receptacle and the size of another strength to another storage receptacle, agitating the sizes in the storage receptacles less violently than in the mixing receptacle, combining the liquids from the storage receptacles in predetermined ratio to form an active size of strength different from the strength of either of said liquids and causing the active size to circulate in a path that includes one of the storage receptacles, and a plurality of slashers in which it may be simultaneously used at the same or different strengths.

26. A sizing apparatus comprising a source of sizing liquid, a receptacle in which the liquid is used, means for rapidly filling the receptacle through an opening of relatively large cross section and for thereafter maintaining a limited continuous flow through a free opening of smaller cross section, said last named opening being of a shape such that substantially the greatest area is secured with substantially the least peripheral dimension whereby a relatively small continuous flow of liquid is insured without clogging.
